UNITED STATES PATENT OFFICE.

JOHN A. FENTON, OF OAKLAND, CALIFORNIA.

DESIGN FOR A CHAIR.

48,587.

Specification for Design.

Patented Feb. 22, 1916.

Application filed November 15, 1915. Serial No. 61,696. Term of patent 3½ years.

To all whom it may concern:

Be it known that I, JOHN A. FENTON, a citizen of the United States, residing at Oakland, in the county of Alameda and State of California, have invented a new, original, and ornamental Design for Chairs, of which the following is a specification, reference being had to the accompanying drawing, forming part thereof.

The figure is a view in perspective, showing my new design.

I claim:

The ornamental design for a chair, as shown.

In testimony whereof I affix my signature.

JOHN A. FENTON.
